UNITED STATES PATENT OFFICE.

CECIL F. DAWSON, OF EASTON, PENNSYLVANIA, ASSIGNOR TO INDIVIDUAL DRINKING CUP COMPANY, INC., OF EASTON, PENNSYLVANIA, A CORPORATION OF PENNSYLVANIA.

APPARATUS FOR SECURING CLOSURE CAPS TO PAPER RECEPTACLES.

Application filed December 11, 1923. Serial No. 680,036.

This invention relates to an improved apparatus for securing closure caps to paper receptacles, and while susceptible of a wide range of usefulness in providing closed paper containers or packages for various purposes it is especially applicable to paper cups that are used for serving ice cream and drinks to provide temporary covers or closures for said cups when the ice cream or 10 drinks are to be carried from the soda fountain to the consumer.

The object of the invention is to provide an improved simple, efficient apparatus whereby closure caps can be quickly inserted within paper receptacles of tapering form to effect an efficient interlocking engagement of the same therewith without the necessity of preliminary or separately preparing a groove or seat in the receptacle 20 to receive the marginal portion of the closure cap, and without fracturing or damaging the receptacle so that it is possible to employ paper drinking cups or other containers in the usual form free from a 25 groove at the upper end thereof when not requiring a cover, and to readily convert the cup into a closed package of inexpensive construction, when desired.

In accordance with the invention a paper 30 cup or other container of tapering form is supported exteriorly and held confined inwardly of its outer end portion against distortion, and while so supported and held a closure cap consisting of a stiff paper disk 35 of the proper size to correspond with the size of the larger end portion or mouth of the paper receptacle is forced uniformly and evenly into the outer end of the receptacle with sufficient pressure and to a sufficient 40 distance to stretch and bend outwardly the side wall of the receptacle to effect a secure interlocking connection between the parts, the wall of the receptacle above the point of support being given a slight outward 45 bulge by the insertion of the cap and a groove or seat formed at the interior of the receptacle in which the marginal portion of the cap is firmly seated.

The invention comprehends a tubular or 50 chambered holder or support adapted to encompass the major portion of the receptacle below the outer end portion thereof in which the closure cap is to be inserted, said tubular or chambered holder being of a size

and shape corresponding to that of the major portion of the receptacle to closely fit about and support the same against distortion, and said holder or support having an annular shoulder at its outer end portion with an adjoining annular flange or part 60 that is of greater diameter than the diameter of and extends in spaced relation with the upper end portion of a receptacle when seated in the holder prior to the application of the closure cap thereto, said annular 65 shoulder and adjoining annular flange or part of the holder serving to assist in the formation of the seat or groove in the receptacle for the closure cap when the closure cap is forced therein. The invention also 70 contemplates a presser member or plunger provided with means for holding a closure cap thereon and adapted to force the closure cap evenly into the end portion of the receptacle while the latter is supported in 75 the holder together with means for regulating the distance the closure cap is forced into the receptacle and the pressure exerted upon the side wall thereof. The invention 80 further comprehends, in combination with the other elements referred to, means for feeding closure caps singly to the plunger or presser member in proper centered relation therewith, and also cup removing or 85 ejecting means for the holder.

The invention, with other objects and advantages thereof, and the particular construction, combinations, and arrangements of parts comprising the same will be understood from the hereinafter contained detail 90 description, when considered in connection with the accompanying drawings, forming part hereof, and illustrating embodiments thereof.

In the drawings:

Figure 1 is a longitudinal section of a paper cup seated in the holder prior to the insertion of a closure cup therein, the presser member or plunger with a closure cap thereon being shown, in part section and 100 part side elevation, above the upper end portion of the cup in centered relation therewith.

Figure 2 is a detail section of the upper portion of the holder and upper part of 105 the receptacle after a closure cap has been applied thereto.

Figure 3 is a detail section on an en-

2

larged scale of an upper portion of the holder, and an upper portion of a receptacle and closure cap secured in interlocking relation.

5 Figure 4 is an inverted plan view of the presser or plunger member.

Figure 5 is a detail plan of a closure cap.

10 Figure 6 is a detail view of a valve device for controlling the suction holding means of the plunger.

Figure 7 is a longitudinal section of the magazine or holder for a stack of closure caps.

15 Figure 8 is a top plan view of the magazine and feeding means.

Figure 9 is a view similar to Figure 7 showing the presser or plunger member engaging the feeding means of the magazine and extending within the magazine in the 20 operation of applying a closure cap thereto.

Figure 10 is a side elevation, with parts shown in section, of a modified form of the plunger mechanism.

25 Figure 11 is a detail inverted plan of the plunger illustrated by Figure 10.

Figure 12 is a top plan view of the modified construction illustrated by Figure 10 and also showing diagrammatically in plan the holder and feeding means for a stack of 30 closure caps.

Figure 13 is a detail top plan view of the upper end of the standard of the construction illustrated by Figure 10.

35 Referring particularly to Figure 1 of the drawings, *a* designates a paper receptacle of tapering form, the particular receptacle illustrated, by way of example, being one of the well known constructions of paper drinking cups commonly employed for serving drinks at soda fountains, the same being of trunco-conical shape and having a bottom *a'*, a side wall *a²* and an outwardly curved or rolled top flange *a³*. *b* designates a closure cap consisting of a paper disk of the required strength and stiffness. The cap *b* is preferably, as shown, of a diameter slightly less than that of the upper end of the receptacle *a* so that the same can readily enter within the upper end of the receptacle.

45 The support or holder for the receptacle, in this instance, is shown as a metal block *1* having an interior chamber of a shape and size corresponding to that of the paper cup or other container *a* to closely surround the

50 major portion of the receptacle below the point to which the closure cap is to be inserted into the larger upper end portion of the receptacle, the said chambered support extending over the upper part of the receptacle a sufficient distance to afford the necessary support for the receptacle adjacent the

55 point of insertion of the closure cap while at the same time permitting of the necessary stretching or bending outwardly of said upper portion of the receptacle to form a seat

or groove therein for the marginal portion of the closure cap. The receptacle holder or support *1* has an annular shoulder *2* at its upper marginal edge, and an adjoining surrounding wall part or flange *3* that is of greater diameter than the diameter of and which extends in spaced relation with the adjacent upper end portion of a receptacle when seated in the holder prior to the application of a closure cap thereto, said annular shoulder *2* and the adjoining surrounding wall portion or flange *3* serving to assist in the formation of the seat or groove in the wall of the receptacle for the closure cap when the closure cap is forced therein by the plunger.

4 designates a plunger or presser member in the form of a plug or block having a lower trunco-conical reduced part *5* and an upper adjoining cylindrical enlarged part *6*.

85 The bottom face *7* of the lower part of the plunger or presser member *4* is of substantially the same diameter as that of the closure disk *b* and is adapted to enter the receptacle. The plunger *4* is provided with suction means for holding a closure cap *b* thereon, said means including a passage leading through the plunger to the bottom face thereof together with suction creating means connected with said passage. The plunger *4* is shown, in the present instance, provided with an interior chamber *8*, openings *9* leading therefrom to its bottom face *7*, and a passage *10* leading through the same from its upper face to said chamber *8*.

100 12 designates a flexible hose connection leading from the upper end of the passage *10* to a vacuum pump *12^a*. 13 designates a short tubular hand grip part having a detachable threaded connection with a collar *14* on a nipple *15* engaging the threaded wall of the upper portion of the passage *10* in the plunger *4*. (See Figure 1 of the drawings.)

105 The enlarged upper part *6* of the plunger *4* is of a diameter greater than that of the larger end of the receptacle *a*, and is adapted at its lower face to engage the outer end or flange *a³* of the receptacle, said enlarged upper part *6* serving as a stop to limit the distance the lower part *5* of the

110 presser member or plunger can force the closure cap into the receptacle and the degree of pressure to which the side wall of the receptacle is subjected, the cap being inserted into the receptacle a predetermined distance nicely gaged in accordance with the size of the closure cap relative to the outer end of the receptacle, and the character of material used, etc., to produce the desired interlocking of the parts without fracturing or crushing the receptacle.

115 Referring particularly to Figures 7, 8 and 9 of the drawings, the means for applying closure caps singly to the face of the plunger in proper centered relation therewith

comprises a magazine or holder for a stack of closure caps *b* equipped with suitable spring pressed follower means, and having at its delivery end portion cap retaining means and means for guiding the plunger in centered relation with the stack of closure caps therein.

The magazine is shown as comprising a cylindrical body part 16 and a supporting base 17, the body part of the magazine 16 having flanges 16' which are detachably secured to the base 17 by screws 18. 19 designates the follower for the magazine and 20 a coiled expansion spring for the follower.

The plunger guiding and cap retaining and feeding means comprises a plurality of yieldable fingers 21, said fingers having inwardly inclined or beveled face portions 21^a adapted to engage the marginal edge portions of the closure caps *b*, and with outwardly inclined or beveled faces 21^b for engagement by the plunger 4. The yieldable fingers are shown as consisting of small head or block portions 21 carried at the upper ends of spring members 22, the lower ends of said spring members 22 being riveted or otherwise suitably secured to the side wall or part 16 of the magazine, the upper portion of the part 16 being provided, as shown, with longitudinal slots 23 through which the finger portions 21 are adapted to work. In the application of a closure cap to the plunger 4, the plunger is forced downwardly into the magazine, the same engaging the beveled face portions 21^b of the fingers 21 being guided thereby into centered relation with the stack of caps *b* within the magazine, at the same time the fingers 21 are expanded or forced outwardly by the plunger, the uppermost cap within the container being released and withdrawn from the magazine in the withdrawal of the plunger 4.

The magazine may be loaded with a stack of closure caps by forcing the same therein through its delivery end portion, or the holder may be charged with closure caps by detaching the part 16 of the magazine from the base 17 and inserting the stack of caps into the lower end of the part 16 after first removing the follower 19 and spring 20.

In practicing the invention, a receptacle *a* is positioned within the holder 1. A closure cap *b* is supplied to the bottom face of the plunger or presser member 4 in centered relation therewith by forcing the plunger or presser member into the magazine, and the closure cap *b* held on the plunger or presser member by the suction holding means thereof, is then forced inwardly into engagement with the side wall of the receptacle by the plunger or presser member 4, the latter being adapted to be operated by hand by pressing or tapping thereon. After the clo-

sure cap has been forced into engagement with the side wall of the receptacle, upon withdrawal of the plunger or presser member, the hold exerted by the suction means upon the closure cap is broken, the closure cap being left seated in place in secure interlocking relation with the receptacle, (as shown in Figures 2 and 3 of the drawings), the frictional engagement between the closure cap *b* and the side wall of the receptacle *a* being such as to overcome the holding force exerted by the suction means, which is, as will be readily understood, relatively slight, just sufficient to hold the relatively light closure cap centered upon the bottom face of the plunger. If desired, a valve 24 may be employed, said valve being adapted to cut off communication with the suction means and establish communication between the suction chamber 8 of the plunger and the atmosphere to relieve the suction on the cap after the same has been forced into interlocking engagement with the receptacle.

Means is provided for ejecting or removing the receptacle from the holder 1 after the insertion of the closure cap *b* therein. For this purpose, in the particular construction shown, the support or holder 1 is provided with a separable bottom part 1^a conforming to the configuration of the bottom *a'* of the receptacle and adapted to be moved longitudinally of the chamber of the support or holder. 1^b designates an operating stem for said movable bottom part 1^a, said stem being provided with a handle 1^c. The movable bottom part 1^a normally occupies the position illustrated in Figure 1 of the drawings. As will be understood by forcing the bottom part 1^a outwardly from its normal position through the medium of the operating stem 1^b, a receptacle within the holder will be released and expelled or forced outwardly therefrom.

In Figures 10, 11, 12 and 13 of the drawings, is illustrated a modified form of plunger and operating means therefor associated with the receptacle holder or support and the cap holding and feeding means. In this form of apparatus 25 designates the receptacle holder or support and 26 the closure cap magazine, these parts being the same in form as in the constructions previously described. 27 designates the plunger or presser member carried on the lower end of a rod 28 mounted for reciprocation in an arm 29, which is pivotally mounted on a standard 30 to swing horizontally, the arm 29 being adapted to be swung to position and support the plunger directly over the receptacle holder or support 25 and to one side thereof to a position over the magazine 26. Means is provided to lock the arm in its position when supporting the plunger over the receptacle support or holder 25.

Any suitable means may be employed for this purpose, the particular locking means shown in the drawing comprising a spring latch 31 adapted to engage notches 32 and 33 in the upper part of the support 30, and the inner end of the arm 29 respectively. 5 34 designates a collar on the upper end of the plunger rod 28 adapted to engage the arm 29 and limit the downward movement 10 of the plunger or presser member 27. 36 is a coiled expansion spring interposed between a knob or handle 37 on the upper end of the plunger rod 28 and the arm 29 and acting to return the plunger to its upper 15 most position. A collar 38 on the plunger rod serves as a stop to limit the extent of upward movement of the plunger rod. The plunger 27 is provided with closure cap holding means similar to that of the plunger 20 illustrated in Figure 1 of the drawings. 39 designate the interior suction chamber of the plunger or presser member 27. 40 designates the openings leading from said suction chamber 39 to the bottom face of the 25 plunger or presser member, 41 the passage leading from said chamber to the upper face of the plunger or presser member, and 42 is the flexible hose connection leading from the upper end of the passage 41 to the 30 suction creating means (not shown). 43 designates the valve in the flexible hose connection for cutting off communication with the suction creating means and to establish communication between the interior suction 35 chamber 39 of the plunger or presser member 27 and the atmosphere.

My improved apparatus, as hereinbefore set forth, provides for quickly and easily securing closure caps to paper receptacles 40 of tapering form. It will be noted that by the provision of the means for applying closure caps singly to the plunger in proper centered relation therewith, and for carrying the closure cap by the plunger, the cap 45 is definitely located in centered relation relative to the plunger and the open end of the receptacle in the application of the closure cap thereto. The preliminary or separate grooving or shaping of the receptacle to 50 provide a bulge or seat portion to receive and interlock with the marginal portion of the cap is entirely avoided, the invention making it possible to use drinking cups or containers in the usual continuous smooth 55 form or free from a groove at the upper mouth portion thereof, and to readily convert such cups into closed packages or containers, as desired, the packages so formed being of an inexpensive nature.

60 It will be understood that the invention is applicable to secure closure caps to various kinds of paper receptacles other than that of the particular form of drinking cup shown in the drawings, and that the par-

ticular constructions of apparatus shown 65 may be modified and changes made therein, as will appeal to those skilled in the art, and falling within the scope of the appended claims, without departing from the 70 spirit of the invention.

What I claim is:

1. An apparatus for securing closure caps to paper receptacles, said apparatus including means for supporting the receptacle, a plunger member adapted to force a closure 75 cap into the receptacle, means for holding a closure cap on the face of the plunger, and means for feeding closure caps to and in centered relation with the face of the plunger, said means including a magazine 80 adapted to support a stack of closure caps for engagement at one end by the plunger, follower means for the magazine, and said magazine having an open longitudinally disposed delivery end part provided with cap 85 retaining means adapted to be engaged and actuated by the plunger to release a closure cap from the stack when the plunger is moved longitudinally to engage the end of the stack of caps. 90

2. An apparatus for securing closure caps to paper receptacles, said apparatus including means for supporting the receptacle, a plunger member adapted to force a closure 95 cap into the receptacle, means for holding a closure cap on the face of the plunger, and means for feeding closure caps to and in centered relation with the face of the plunger, said means including a magazine adapted to hold a stack of closure caps 100 for engagement at one end by the plunger, a spring pressed follower for the magazine, and said magazine having an open longitudinally disposed delivery end part provided with a plurality of spring closure cap 105 retaining fingers adapted to be engaged and moved outwardly by the plunger to release a cap from the stack when the plunger is moved to engage the end of the stack of caps. 110

3. An apparatus for securing closure caps to paper receptacles, said apparatus including means for supporting the receptacle, a plunger member adapted to force a closure 115 cap into the receptacle, means for holding a closure cap on the face of the plunger, and means for feeding closure caps to and in centered relation with the face of the plunger, said means including a magazine adapted to hold a stack of closure caps 120 for engagement at one end by the plunger, a spring pressed follower for the magazine, and said magazine having an open longitudinally disposed delivery end part provided with yieldable cap retaining fingers 125 adapted to be engaged and moved outwardly by the plunger to release a closure cap from the stack when the plunger is moved to en-

gage the end of the stack of caps, said yieldable fingers having beveled faces for engagement by the plunger.

4. An apparatus for securing closure caps to paper receptacles, said apparatus including means for supporting the receptacle, a plunger member adapted to force a closure cap into the receptacle, means for holding a closure cap on the face of the plunger, and means for feeding closure caps to and in centered relation with the face of the plunger, said means including a magazine adapted to hold a stack of closure caps for engagement at one end by the plunger, a spring pressed follower for the magazine, and said magazine having an open longitudinally disposed delivery end part provided with yieldable cap retaining fingers adapted to be engaged and moved outwardly by the plunger to release a closure cap from the stack when the plunger is moved to engage the end of the stack of caps, said yieldable fingers having inwardly inclined cap engaging faces and adjoining outwardly flaring faces for engagement by the plunger.

5. An apparatus for securing closure caps to paper receptacles, said apparatus including means for supporting the receptacle, a plunger member adapted to force a closure cap into the receptacle, means for holding a closure cap on the face of the plunger, and means for applying closure caps to and in centered relation with the face of the plunger, said means including a magazine adapted to hold a stack of caps for engagement at one end by the plunger, a spring pressed follower for the magazine, and said magazine having an open longitudinally disposed delivery end part provided with means for engagement by the plunger and acting to guide the plunger in centered relation with the stack of closure caps.

6. An apparatus for securing closure caps to paper receptacles of tapering form, said apparatus including means of tubular form

tapering interiorly to confine the side wall of the receptacle inwardly of the larger end thereof against lateral distortion, said means having an annular shoulder at its upper margin and an adjoining flange portion of greater diameter than and extending in spaced relation with the adjacent portion of a receptacle when seated within said receptacle holding means prior to the application of a closure cap thereto, in combination with a plunger to force a closure cap into the larger end of the receptacle, said plunger having a bottom face of a diameter greater than the interior diameter of said holding means directly below said shoulder to extend over and in opposing relationship with said shoulder, said annular shoulder and adjoining flange part acting to assist in the formation of a seat in the receptacle to receive the closure cap.

7. An apparatus for securing closure caps to paper receptacles, said apparatus including means for supporting the receptacle, a plunger member adapted to force a closure cap into the receptacle, means for holding a closure cap on the face of the plunger, and means for feeding closure caps to and in centered relation with the face of the plunger, said means including a magazine adapted to hold a stack of closure caps for engagement at one end by the plunger, a spring pressed follower for the magazine, and said magazine having an open longitudinally disposed delivery end part provided with longitudinal slots and with yieldable cap retaining fingers having upper portions extending into said slots and adapted to be engaged and moved outwardly by the plunger to release a cap from the stack when the plunger is moved to engage the end of the stack of caps.

In testimony whereof I hereunto affix my signature.

CECIL F. DAWSON.
